UNITED STATES PATENT OFFICE.

ERNEST J. SHAFFER, OF TULSA, OKLAHOMA.

SUCKER-ROD-CONNECTING MEANS.

Application filed December 24, 1921. Serial No. 524,688.

To all whom it may concern:

Be it known that I, ERNEST J. SHAFFER, a citizen of the United States, residing at Tulsa, in the county of Tulsa and State of Oklahoma, have invented a certain new and useful Improvement in Sucker-Rod-Connecting Means, of which the following is a full, clear, and exact description, reference being had to the accompanying drawings.

10 This invention relates to an accessory for use by drillers and operators of deep wells. Frequently in deep well operations the string of sucker rods through which the drills are operated or the bump pistons actuated separates in the well tubing, and in the great majority of cases this separation is the result of one of the sucker rods breaking intermediate its enlarged ends where it is coupled to adjoining rods of the string, although the 20 break occasionally occurs at the box of coupling.

It is the primary purpose of my invention to provide means through which an operator is enabled to repair a broken sucker rod 25 without the necessity of pulling the entire string of rods from the tubing.

A further object is to provide means of the aforesaid character that may be very conveniently and efficiently used as a fishing 30 tool for recovering broken sucker rods from well tubing.

Other objects are to provide a grappling device for the attainment of the foregoing end which is very simple of construction; is 35 comparatively inexpensive of production; is strong, durable, and immune from disorder, and which has a double action in attaching itself to a rod that makes its hold thereon exceedingly secure, the first, a clamping 40 action resulting from the inherent resiliency of the material whereof the device is formed, and the second, a screw action resulting from the turning of the device upon the rod, the device having the character of a thread 45 cutting die and producing threads upon the rod.

The foregoing objects, and others which shall appear as this description proceeds, are attained through the forms of the invention illustrated in the drawing accompanying and forming a part hereof and wherein Fig. 1 is an elevational view of one form of the invention; Fig. 2 is a central longitudinal section thereof; Fig. 3 is a cross section on the line 3—3 of Fig. 1; Fig. 4 is an elevational view of another form

of the invention; Fig. 5 shows a further modification; Figs. 6 and 7 are views illustrating the manner in which the forms of the invention shown in Figs. 1 and 4, respectively, operate within a tubing; Fig. 8 is a central longitudinal section through a form of the invention wherein the bore is tapered so as to catch all sizes of sucker rods; and Fig. 9 is a similar view of another 65 form of the invention wherein the bore is graduated to catch rods of various diameters, as well as the boxes or couplings thereof.

The form of the device illustrated in Figs. 1 to 3 comprises a substantially cylindrical body portion 1, which is reduced in diameter throughout the greater portion of its length upwardly from its lower end and which terminates at its upper end in a threaded pin 2 that is adapted to be received by a coupling member 4, of a sucker rod 5, as illustrated in Fig. 6. The body portion 1 has a central bore 6 that extends from its lower end to within a comparatively short distance of its upper end, and the bore is threaded, the upper sides of the threads being substantially straight, while the lower sides are inclined, as will be readily seen from an inspection of Fig. 2. This peculiar design of thread greatly enhances the holding quality of the device. The lower end of the body portion is inclined upwardly from its periphery to facilitate the finding of the broken rod when the device is lowered into the tubing. A series of slots 8 extend from the lower end of the body portion 1 to within a short distance of its upper end and divide it into a plurality of prongs 9 which may yield somewhat due to the resiliency of the metal and the fact that the prongs are thinner throughout their upper portions. While three slots 8, and consequently a like number of prongs 9, have proven very satisfactory, it is obvious that any practical number of slots may be made in the body portion and resulting, of course, in a like number of prongs.

This form of the invention is intended for use primarily as a fishing tool, although it may be used as a repair unit. In using it as a fishing tool and assuming that a string of sucker rods has parted somewhere within the well tubing, the section above the break is withdrawn from the tubing and the broken portion of the rod at its lower end is unscrewed, and the device of my invention is attached to the socket 4 of the rod 5,

as shown in Fig. 6. The device is then lowered into the tubing by means of the sucker rods until it is brought into engagement with the broken end of the rod that is lost in the well. The converging lower end of the device, striking the broken end of the rod, centers and directs it into the bore 6, after which the device is forcefully pressed down over the rod and turned in a direction 10 to screw it onto the rod by means of a wrench applied to a square on the string of rods where it projects above the tubing. The device is thus positively united to the broken sucker rod enabling the lost section of the 15 string to be readily withdrawn from the tubing. Or, by reason of the very secure connection effected by the device, the drilling or pumping operation may be proceeded with if desired. Attention is called to the 20 character of the threads of the bore 6, as they are illustrated in Fig. 3. It will be observed that along one edge of each of the prongs 9, the threads are chamfered at 10 while adjacent the opposite edge of the 25 prong the threads are sharp. It is the sharp edges of the threads which cut into the rod when the device is turned in a direction to thread it onto the rod. The opposite ends of the thread, being chamfered as shown, prevents the threads cutting deeper into the rod 30 as the device is being unscrewed due to the tension of the prongs 9. This enables the device to be easily removed from the rod.

The form of the invention illustrated in 35 Fig. 4, while it may be used as a fishing tool, is primarily intended for use as a temporary repair unit for joining together the severed ends of a broken rod, enabling the pumping operation to be proceeded with immediately 40 after the rod is connected by means of the device, and without the necessity of pulling the entire string.

This form of invention comprises an elongated body portion which, at its longitudinal center, is flattened on opposite sides, as indicated at 12, to provide means for turning the device as by the application of a wrench thereto. At each end, however, the present device is substantially identical with 45 that described above, and the parts thereof bear the same reference numerals as the corresponding parts of the previous form, augmented by the exponent "a."

When a break occurs in a string of sucker rods the portion above the break is withdrawn from the tubing and the device is applied thereto, cutting its own threads within the end of the rod and thus attaching itself very securely to the rod. The rods are 55 then lowered into the tubing and the lower end of the device is attached to the other severed end of the rod in the manner illustrated in Fig. 7, after which the drilling or pumping operation may continue.

Fig. 5 illustrates a form of the invention

that is identical with the form illustrated in Figs. 1 to 3 except that the slots 8^b stop short of the lower end of the body portion 1^b. Here the segmental sections 9^b between the slots 8^b may yield somewhat intermediate their upper and lower ends so as to create the required pressure on the rod. The lower end of the bore of this form of the device is shown as flared slightly as indicated in dotted lines, to facilitate the attachment of the device to the rod. This same feature may be included in the other modifications, although it is not regarded as so essential in view of the yielding character of the prongs 9 and 9^a throughout their entire lengths. The closed slots 8^b may be substituted for the open ended slots in the form of the invention illustrated in Fig. 4.

In order to adapt the device to the catching of sucker rods of all diameters, the bore of the device may be tapered as illustrated in Fig. 8. Here the body portion 1^c is shown as divided into prongs 9^c by slots 8^c that extend to the end of the body portion, although in lieu thereof the slots may stop short of the end, as in Fig. 5. Obviously the tapered bore may be employed in connection with the form of the invention illustrated in Fig. 4, adapting this modification for use with all sizes of sucker rods.

In using the devices having tapered bores, the rods enter until they find the zone of the bore having a diameter substantially equal to their own whereupon the connection is made, the smaller rods naturally entering further than those of greater diameter, as illustrated in Fig. 8 where the rods are represented by dot-and-dash lines.

To take care of those situations where the break occurs at a box or coupling, as when a pin breaks, I modify the invention as shown in Fig. 9, so that at its lower end the bore is large enough to receive a box 10. The bore converges upwardly slightly and then continues straight until it meets a shoulder 11 which separates the box receiving portion of the bore from the rod socket 12. This socket is also shown as a tapered bore enabling it to grasp rods of different diameters. This form of the invention, then, will be reorganized as one adapted to the catching of all sizes of sucker rods and their boxes or couplings.

In this form, the body portion 1^d is shown as divided into prongs 9^d by slots 8^d which extend to the end of the body portion. However, the shorter slots may be substituted therefor, as in the form of the invention illustrated in Fig. 5.

Having thus described my invention, what I claim is:

1. A device for recovering broken sucker rods from well tubing consisting of an elongated body portion having a threaded bore and slotted longitudinally at points spaced

apart circumferentially of the bore thereby to provide resilient parts capable of yielding radially, said parts being arranged to grasp between them the broken end of a 5 sucker rod and hold the same firmly by reason of the inherent resiliency of said parts and the presence of the thread.

2. A device for recovering broken sucker rods from well tubing comprising an elongated body portion having a bore, said body portion being slotted longitudinally at points spaced apart circumferentially of the bore thereby to provide resilient parts that are capable of yielding outwardly, said parts 10 being arranged to grasp between them the broken end of a sucker rod and having cutting portions which are adapted to cut into the rod when the body portion is turned with respect to the rod, said parts, through their 15 inherent resiliency, tending to force the cutting portions into the rod.

3. A device for recovering broken sucker rods from well tubing comprising a substantially cylindrical body portion having a threaded bore and slotted longitudinally at 25 points spaced circumferentially apart thereby to provide resilient segmental parts capable of yielding radially so that said parts will grasp between them the broken end of a sucker rod when forced thereover, the inherent resiliency of the parts causing the thread portions of said parts to cut into the rod when the device is turned in a given direction, the thread portions of each segmental part being chamfered along one of 30 the lateral edges of said part so as to override the rod when the device is turned in the opposite direction.

In testimony whereof, I hereunto affix my signature.

ERNEST J. SHAFFER.
